UNITED STATES PATENT OFFICE.

FELIPE HECHT, OF GENEVA, SWITZERLAND.

WATCH-PLATE.

SPECIFICATION forming part of Letters Patent No. 638,510, dated December 5, 1899.

Application filed November 18, 1897. Serial No. 658,911. (No model.)

To all whom it may concern:

Be it known that I, FELIPE HECHT, a citizen of the Kingdom of Spain, residing at Geneva, Switzerland, have invented certain new and useful Improvements in Watches, of which the following is a specification.

This invention relates to improvements in watches; and the object of the invention is to facilitate the removal of a portion of the movement for purposes of repair or examination without taking the entire movement from the case, and particularly to permit the separate removal of the barrel, thus giving easy access to the interior of the movement. The object is, further, to provide a click-spring and abutment for the same of improved construction and arrangement.

To these ends the invention consists in the combination, with a barrel-bridge provided with an extension having a recess or depression and an abutment at the junction of the bridge and extension, of a winding-wheel supported above said barrel-bridge and an expansile click-spring located in said recess, fixed against movement longitudinally therein and engaging by its click the teeth of said winding-wheel, said click being provided at its outer side with a heel engaging said abutment and the shank of said click-spring extending from the click adjacent to said heel along the recess-wall.

In the accompanying drawings, Figure 1 is a plan view of a watch-movement embodying my invention. Fig. 2 is a plan view of the barrel-bridge and click-spring. Fig. 3 is a plan view of the crown-bridge, and Fig. 4 is a vertical section of the movement on line *x y z* of Fig. 1.

Similar letters of reference indicate corresponding parts.

Referring to the drawings, A represents the recessed pillar-plate of the watch-movement, upon which are supported the barrel-bridge B and the crown-bridge C. The barrel-bridge B is attached to the pillar-plate A by means of a screw *b*, which passes through the extension *B'* of the same and the usual studs and supports in a suitable bearing a winding-wheel R, having the center *r*, and at the opposite side of the barrel-bridge, in the recess of the pillar-plate, are located the usual spring and barrel. A click-spring D is retained in a

circular recess or depression of the barrel-bridge by a pin *d*, which prevents longitudinal movement of the spring in the recess, the outward tension of said spring keeping the click *d'* of the same in position in engagement with the teeth of the winding-wheel R and the shank of the spring located along the recess-wall. The crown-bridge C is secured upon the pillar-plate A by means of a single screw *c*, which passes through the crown-wheel *c'* and the crown-bridge and forms the axle of the crown-wheel and of the usual studs. The bridge M of the center wheel is also secured by means of a single screw *m* and the usual studs, as also the bridges N and O of the escapement-wheel and of the balance-wheel, respectively. The bridges M and N may be made in one piece, if desired, so as to form one bridge, which would be secured by means of the screw *m*.

The barrel-bridge B is itself recessed in its main part for receiving the winding-wheel, as shown in Fig. 2, and the recess of the extension opens into the main recess for the winding-wheel. The click *d'* is provided at its outer side with a heel *d²*, which normally engages an abutment *d³*, formed at the junction of the recess-walls of the main portion and extension of the bridge, the shank *d⁴* of the click-spring extending along the adjacent recess-wall of the extension. By this construction and arrangement of the click-spring, abutment, and recess-wall the positive and reliable engagement of the click with the winding-wheel and securing of the click against movement when so engaged are produced. As the click does not enter the teeth of the winding-wheel with pressure, but is limited in its outward movement so as normally only to enter the path of the teeth of the winding-wheel, it is possible to replace the winding-wheel, should the same have been removed, without holding the click-spring in compressed condition during the operation.

The improvements above described are the means of effecting a large saving in expense in making watch-movements, as they reduce the number of parts and facilitate also the repairing of the movement when necessary.

Having thus described my invention, I claim as new and desire to secure by Letters Patent—

In a watch, the combination, with a barrel-bridge provided with an extension having a recess or depression, and an abutment at the junction of the bridge and extension, of a 5 winding-wheel supported above said barrel-bridge, and an expansile click-spring located in said recess, fixed against movement longitudinally therein, and engaging by its click the teeth of said winding-wheel, said click being provided at its outer side with a heel 10 engaging said abutment, and the shank of said

click-spring extending from the click adjacent to said heel along the recess-wall, substantially as set forth.

In testimony whereof I have signed my 15 name to this specification in the presence of two subscribing witnesses.

FELIPE HECHT.
